(57) **CLAIM**

The ornamental design for a tree branch wrap, as shown and described.

DESCRIPTION

FIG. 1 is a perspective view of a tree branch wrap shown in a flattened configuration, according to the invention;

FIG. 2 is a top plan view thereof;

FIG. 3 is a perspective view of the tree branch wrap of FIG. 1 shown in a rolled configuration;

FIG. 4 is a top plan view thereof;

FIG. 5 is a bottom plan view thereof;

FIG. 6 is a side view thereof; and,

FIG. 7 is a top plan view of a tree branch wrap of FIG. 3 shown in a rolled and secured configuration.

The broken lines represent portions of the article and form no part of the claimed design.
